UNITED STATES PATENT OFFICE.

HIRAM J. WHITE, OF BOSTON, MASSACHUSETTS, ASSIGNOR TO HOLMES, BOOTH & HAYDENS, OF WATERBURY, CONNECTICUT.

LAMP-BURNER.

SPECIFICATION forming part of Reissued Letters Patent No. 9,498, dated December 7, 1880.

Original No. 102,897, dated May 10, 1870. Application for reissue filed April 22, 1880.

To all whom it may concern:

Be it known that I, HIRAM J. WHITE, of Boston, county of Suffolk, State of Massachusetts, have invented an Improvement in Lamp-Burners, of which the following is a specification.

Lamps have been made with pendent springs acting within the base of the chimney, and an outward flange at the lower end of each spring 10 supported the chimney. Air-distributors have been made that are flat, convex, and conical. These usually have had more or less of a rim around them, that prevented the surface of the air-distributer being wiped off clean with facility. The air-distributer has been raised above the chimney-rest, but the springs or lateral supports to the chimney have been upon a cylinder that is above the air-distributer and is below and separate from the removable 15 deflector; hence the chimney acts with a leverage against the cylinder to loosen it from the air-distributer.

My invention is made for facilitating the cleaning of the air-distributer, for simplifying 20 the construction of the lamp, and for increasing its efficiency and durability.

In my lamp the air-distributer is raised to facilitate cleaning. The cone or deflector is of an ordinary dome shape, and its lower edge 25 directly surrounds the air-distributer and rests upon a shoulder formed in the metal, so as to be directly supported thereby. The air-distributer is near the upper end of the wick-tube, so that the deflector only requires to be 30 of an ordinary height.

The chimney-springs are in the metal around the air-distributer. They do not form a chimney-rest, but the chimney-support is rigid and below the springs.

In the drawings, Figure 1 is an elevation of the burner. Fig. 2 is a plan of the same. Fig. 3 is a vertical section. Fig. 4 is a plan of the burner with the cone or deflector removed. Fig. 5 is a side elevation of the parts 45 shown in Fig. 4; and Fig. 6 is a side view of the cone or deflector detached.

The wick-tube *a*, wick-raiser *b*, screw-base *c*, and cap rising above and forming a cover to the ratchet and a support for the wick- 50 tube, are of any usual or desired character.

The chimney-holder is made with a base or

chimney-support, *d*, upon which the lower end of the chimney rests.

The springs *e* that hold the chimney act inside such chimney. They are shown as tongues 55 formed by horizontal and vertical incisions in the metal cylindrical portion *f* of the burner. The ends of the springs point downwardly, so as to allow the chimney to be placed over them with facility.

The air-distributer *t* is made of a metal plate with numerous small holes. It is around the wick-tube and extends outwardly from the same, and is bent downwardly to form the shoulder *i*, upon which the base of the cone or 65 deflector *h* rests. The air-distributer is above the shoulder *i*, upon which the cone or deflector *h* rests, so that it can easily be kept clean and free from carbonaceous matter, which is liable to obstruct the holes or to make 70 the lamp smell.

The handles at *m* are upon opposite sides of the cone or deflector, to facilitate removal, and the base of such cone is notched at *l*, so as to fit upon studs *r*, at the edges of the air-distributer, in order that the flame-slot in the air-distributer may occupy the correct position to the wick; and in Figs. 1 and 6 the cone is shown with vertical incisions that form the base into slightly-yielding springs, to aid in 80 keeping the cone in position.

I claim as my invention—

1. The combination, with the raised air-distributer surrounding the upper part of the wick-tube, of a convex or dome-shaped deflector, the lower edge of which surrounds the raised air-distributer and rests upon a shoulder in the metal, and internally-acting chimney-springs and a rigid chimney-support below the air-distributer, substantially as set forth. 85

2. In a lamp-burner having a raised air-distributer near the upper part of the wick-tube, a convex or dome-shaped deflector, the lower edge of which directly surrounds and incloses the air-distributer, substantially as set forth. 90

Signed by me this 15th day of April, A. D. 1880.

HIRAM J. WHITE.
